UNITED STATES PATENT OFFICE.

SAMUEL DRUGAN AND JOHN SCHOENTHALER, OF TRENTON, NEW JERSEY, ASSIGNEES
TO COCHRAN, DRUGAN & CO., OF TRENTON, NEW JERSEY, A CORPORATION OF NEW
JERSEY.

FLUSH-TANK COVER.

1,030,059.

Specification of Letters Patent.

Patented June 18, 1912.

Application filed April 16, 1910. Serial No. 555,956.

To all whom it may concern:

Be it known that we, SAMUEL DRUGAN and JOHN SCHOENTHALER, citizens of the United States, and residents of Trenton, 5 Mercer county, New Jersey, have invented certain Improvements in Flush-Tank Covers, of which the following is a specification.

Our invention relates to water closet flush tanks, and the object of our invention is to 10 provide an improved form of top or cover, preferably made of vitreous or earthen ware for use with tanks made of the same or similar material.

The present practice, or a practice which 15 has come very much into vogue of late, is to have a tank of the same material as the closet bowl. In order to provide a cover for such tank, the material of which it is composed demands that it be made sufficiently heavy, to avoid breakage by accident or during the burning operation on the one hand, and so that it may be retained in place by its own weight on the other hand, and when made so heavy it is necessary to 20 take extraordinary care and precaution to insure the burning of the same to the desired extent without distortion or other damage before or immediately after being taken from the kiln.

Our improved top or cover is hollow; the 25 advantage of which construction is to reduce the dead weight of the same and at the same time provide a structure possessing all of the features that are desirable for the purpose for which it is intended. We are further enabled to increase the strength of the top or cover and prevent distortion of the same; such distortion being caused by the contraction which occurs during the 30 burning operation.

Our invention is fully shown in the accompanying drawings, in which:

Figure 1, is a perspective view of our 5 improved tank top or cover shown in the position of use; a portion of the tank being indicated by dotted lines; Fig. 2, is a rear elevation of the top or cover; Fig. 3, is a plan view of the same; Fig. 4, is an inverted plan view, and Fig. 5, is a sectional view on the line $a-a$, Fig. 3.

In the drawings herewith, 1 represents the top or cover, the upper surface of which may be ornamental in character or not as desired; which cover is composed of upper and lower walls 2 and 3, and a rear wall 4.

The upper and lower walls may be merged at the front and sides into an ornamental edge 5. The upper wall may be molded while plastic by suitable means in one piece, and the bottom or lower wall may also be 60 molded while plastic in one piece and joined to the upper wall or section, and these two sections are secured together while in the plastic or green state in a manner well known in the art of making vitreous and 65 earthen ware. The rear wall, indicated at 4, may be formed separately and joined to the upper and lower walls or it may be formed integral with the upper wall. It 70 may be hollowed out or recessed as at 7 for a purpose to be described. Apertures 8 may be provided in the lower and rear walls for the escape of vapor which may form in the hollow space during the burning operation, and we have shown a pair of such apertures. It will be understood, however, that 75 more apertures may be provided and in some instances are desirable for the purpose designed, and a number of the same can be formed in the lower wall without affecting 80 the strength of the same or the top or cover.

In order that the top may rest upon and be retained by the wall of the flush tank, we prefer to provide it with a depending edge 9 85 at the front, and the bottom with lugs 10 set inwardly some distance from the edge and of any suitable size; such edge coming over the front of the tank, while the lugs rest behind the wall of the same and serve 90 to position the cover in place. While we have shown a pair of lugs, it will be understood that we may use more if desirable and that a continuous projection paralleling the edge may take the place of such lugs. 95

It is desirable, of course, in the finishing of such a structure that the rear edge or wall bear a definite relation to the front edge of the same as regards distance from said front edge and that it be substantially 100 parallel therewith. To produce this result, it frequently becomes desirable to grind such rear edge or wall. To this end, the rear edge or wall is hollowed in the manner indicated at 7 so that if such grinding 105 operation becomes necessary, the portion of the wall to be reduced will be relatively small in area.

Flush tank tops or covers are usually made of white porcelain, but it will be understood 110

that other materials may be employed, and that they may be of an ornamental character, or not, as may be desired.

We claim:

- 5 1. A hollow cover having top, bottom and rear walls integrally connected together, the bottom wall having a depending edge following the contour of the front and ends of the structure, and the rear wall having a portion of its surface cut away.
- 10 2. A hollow cover having top, bottom and rear walls integrally connected together, the bottom wall having a depending edge following the contour of the front and ends of the structure and a plurality of lugs paralleling said depending edge to afford positioning means for said cover, and the top

wall merging with the bottom wall at the front and ends of the same.

- 20 3. A hollow cover having top, bottom and rear walls integrally connected together, the bottom wall having a depending edge following the contour of the front and ends of the structure, and the bottom wall having a depending portion affording positioning means for said cover.

In testimony whereof, we have signed our names to this specification, in the presence of two subscribing witnesses.

SAMUEL DRUGAN.
JOHN SCHOENTHALER.
